BOX

Julius A. Stock, Chicago, Ill., assignor to W. C. Ritchie and Company, Chicago, Ill., a corporation of Illinois

Application October 17, 1934, Serial No. 748,572

6 Claims.

(Cl. 229—6)

My invention concerns particularly certain features of betterment and advance in the construction of pasteboard and other boxes or receptacles for powder, such as face-powder, and the like.

Heretofore, it has been customary to make such containers by using an ordinary or known type of box, usually round, with an extended-edge bottom, and providing it with a so-called drum formed of a flange, ring or rim and covered over one end with frangible paper or its equivalent, such ring fitting snugly inside of the round wall of the box-body and the paper covering the powder contained in the drum thus housed in the box.

In some cases, the paper may be transparent, such as the so-called "Cellophane", whereby the purchaser or user may observe the powder before the paper or drum-head is ruptured to render it accessible for use.

In powder-containing boxes of this style substantial difficulty in the past has been encountered in preventing the powder from sifting out of, or finding egress from, the box before the paper of the drum has been broken through.

Ordinarily, these boxes are made at a box-makers factory but are filled with the powder at the plant of the manufacturer or seller of the powder.

The designated disagreeable and objectionable sifting or discharge of some of the powder from the box ordinarily occurs by the powder passing out between the ring of the drum and the side wall of the box in which such drum closely and comparatively tightly fits.

Various attempts have been made to overcome such annoying and provoking delivery of the powder from its supposedly tight and sealed container.

The manner in which such boxes are filled with the powder has in a measure made the solution of the problem somewhat more difficult.

The drums are placed closed end down on a table with their open ends up and then they are easily and readily filled with the powder, whereupon the inverted box-bodies are placed over and telescopically assembled with the drums by pressing them down so that the drums enter the bodies, after which the box-covers are applied, thus shielding and protecting the more or less fragile paper drum-heads.

It has been endeavored to glue such powder-filled drums in their boxes, but such efforts have not been successful, partly perhaps because it is difficult to use glue in close association with the powder-filling operation and perhaps partially due to the effect of climatic conditions on the adhesive, not to mention the expense involved in the cost of the adhesive and the application of it, bearing in mind that when these boxes and

drums are made in large quantities and the goods must be sold at comparatively small figures in a highly competitive cosmetic line, the cost of production is an important item.

It has also been suggested to use a band of paraffin on the outer surface of the drum-wall or on the inner surface of the box-body wall to prevent the powder from percolating out between these two portions of the container, but, regardless of whether or not such paraffin will accomplish the desired powder-retaining function, its use is not commercially feasible, because when such boxes are displayed in the sunlight or otherwise subjected even to moderate heat, as in a store window, the paraffin melts and destroys the otherwise pleasing appearance of the container.

Other efforts have been exerted to overcome this powder-sifting difficulty, and while the problem at first appears to be a relatively easy one to solve, experience has clearly demonstrated that when all the factors involved in the situation are given due consideration and weight, the task has been found to be one which has not lent itself to ready solution.

Inasmuch as the open end or mouth of the drum must enter the box-body to effect their assembly, the diameter of such portion of the drum must be sufficiently less than the internal caliber of the box-body to permit their ready and facile fitting of the box-body over such end, and, on the other hand, to preclude the powder from sifting out between the drum and box-body wall, the two parts should fit together quite tightly, these two requirements obviously being somewhat in conflict.

To allow the easily accomplished initial fitting of the box-body over the open mouth end of the drum and to have a tight fit of the greater portion of the drum wall or ring in the box-body, attempts have been made to taper the round drum-wall so that as the telescopic fitting of the two parts proceeds, the drum will fit progressively tighter in the box-body, but experience has shown that in such a construction, by reason of the specified taper, there is a tendency for the drum to work up and to loosen in the box-body.

Accordingly, one of the prime and leading purposes of the invention is to provide a construction which will prevent the escape of the powder and which at the same time is simple in structure and which will not add to the cost of the box.

After considerable investigation, study and experiment, over a period of time, I have at last discovered that this result is capable of accomplishment.

Instead of using a tapered or flaring drum ring or body, I preferably, but not necessarily, employ one of substantially uniform diameter and of such size that the companion box-body can be easily fitted over it to bring about the assembly of the

two parts with facility and dispatch, and, at a part of the drum-ring near its top paper or other rupturable or frangible cover, it is provided with an external, outstanding rib, desirably hollow, as by corrugating or embossing the drum-ring, which when the drum and box-body are fully and completely fitted together presses outwardly against the inner face of the box-body wall to effect an adequate seal between the two, such rib or circular projection, especially if hollow, having adequate elasticity or resiliency to conform to inequalities of shape and surface of the parts involved to permit the necessary occlusion whereby to effect the required sealing of the powder against discharge in any degree.

To enable those skilled in this art to fully understand the invention from both structural and functional standpoints, in the accompanying drawing, forming a part of this specification and to which reference should be had in connection with the following detailed description, a present preferred embodiment of the invention has been illustrated, and, for simplicity, like reference characters have been employed in the views to designate the same structural parts.

In this drawing:—

Figure 1 is a plan view of the box-body and associated powder-containing drum with the box-cover removed; and

Figure 2 is an enlarged cross-section through the complete structure showing the box-cover raised from the box-body.

By reference to these views, it will be apparent that the box-body is composed of the circular or round flange, ring or rim 11 and a bottom disc 12, the two parts being covered and united in the usual way by the paper 13, the one margin 14 of which is folded over and adhered to the under surface of the bottom 12 and the upper or opposite margin 15 of which is folded over into the mouth of the box-body and adhered to the inner surface of its flange or ring. There is nothing novel in such a box-body, as these have been known and manufactured in large quantities over a period of years.

The box-cover characterized as a whole 16, is made in substantially the same manner, and, accordingly, its specific construction need not be further referred to.

The drum comprises a ring or circular wall 17 of slightly less diameter than the box-body wall 11 and of approximately the same height, and a transparent paper drum head or cover 18, the circular margin of which is folded down over a portion of the external surface of the wall or ring 17.

A strip of cover paper 19 extends around the drum and is adhered to the part of the wall 17 not covered by the drum-head margin and also adhered to such folded-over margin, whereby the drum-head is secured tightly over the end of the drum and the outer surface of the curved wall of the drum presents a finished appearance.

The round wall of the drum, remote from its lower edge, at a point covered by the folded margin of the frangible paper drum-head is embossed to provide an outstanding hollow rib or bead 21 extended completely around the drum.

When the powder-filled drum and box-body are telescopically assembled, this bead or rib presses outwardly against the inner surface of the flange of the box-body and seals the space between the two, so that the discharge of powder at that point is overcome.

This construction, while simple, has remedied a fault in the earlier box structures and appar-

ently performs the required function with entire satisfaction.

The invention as described and claimed is not necessarily limited to the exact details of construction presented and these may be modified within proper limits without departure from the heart and essence of the invention and without the loss or sacrifice of any of its benefits and advantages.

For example, it is not essential that the continuous bead or rib be hollow, but the latter characteristic is nevertheless highly desirable. Again, it is not a requisite that such bead be covered by the margin of the drum-head paper or that it be covered by the paper band illustrated and described as extending around the drum.

I claim:

1. A powder-box having a box-body with a bottom and an upstanding wall, a drum having a wall conforming to the general shape of and inserted in said box-body wall and having a powder-retaining rupturable head covering one end of said drum, and a box-cover for said box-body, said drum wall having a peripheral rib extended around said drum wall and bearing against the inner surface of said box-body wall to seal the space between the two to prevent the escape of powder from said drum through said space, the outer surface of said drum-wall and the inner surface of said box-body wall being free from adhesive securing said walls together.

2. The structure presented in claim 1 in which said rib is hollow.

3. The structure presented in claim 1 in which said rib is hollow and embossed in said drum wall.

4. The structure presented in claim 1 in which said rib is at a distance from the lower edge of said drum wall.

5. A powder-box having a box-body with a bottom and an upstanding wall, a drum having a wall conforming to the general shape of and inserted in said box-body wall and having a powder-retaining rupturable head covering one end of said drum, and a box-cover for said box-body, said drum having a peripheral hollow rib embossed therein and extending around said drum wall at a distance from the lower edge thereof, said rib bearing against the inner surface of said box-body wall to seal the space between the two to prevent the escape of powder from said drum through said space, the outer surface of said drum-wall and the inner surface of said box-body wall being free from adhesive securing said walls together.

6. A powder-box having a box-body with a bottom and an upstanding wall, a drum having a wall conforming to the general shape of and inserted in said box-body wall and having a powder-retaining rupturable head covering the upper end of said drum and extended down and secured to the outer surface of said drum wall, and a box-cover for said box-body, said drum wall and the portion of the drum-head material outside of said wall having a peripheral hollow rib embossed therein and extending around said drum wall at a distance from the lower edge thereof, said rib bearing against the inner surface of said box-body wall to seal the space between the two to prevent the escape of powder from said drum through said space, the outer surfaces of said drum-wall and of said portion of the drum-head material outside of said drum-wall, and the inner surface of said box-body wall being free from adhesive securing them together.
